H. W. WEINHART,
ELECTRON DISCHARGE DEVICE,
APPLICATION FILED OCT. 25, 1918.

1,419,528.

Patented June 13, 1922.

Inventor:
Howard W. Weinhardt.

by *J. Roberts* Atty.

UNITED STATES PATENT OFFICE.

HOWARD W. WEINHART, OF ELIZABETH, NEW JERSEY, ASSIGNOR TO WESTERN ELECTRIC COMPANY, INCORPORATED, OF NEW YORK, N. Y., A CORPORATION OF NEW YORK.

ELECTRON-DISCHARGE DEVICE.

1,419,528.

Specification of Letters Patent. Patented June 13, 1922.

Application filed October 25, 1918. Serial No. 259,639.

To all whom it may concern:

Be it known that I, HOWARD W. WEINHART, a citizen of United States of America, residing at Elizabeth, in the county of Union, State of New Jersey, have invented certain new and useful Improvements in Electron-Discharge Devices, of which the following is a full, clear, concise, and exact description.

10 This invention relates to electron discharge devices and has particular reference to means for supporting electrodes within devices of this character, for example, three electrode vacuum tubes.

15 An object of this invention is to provide means whereby an electrode may be supported in operative relation to other electrodes and yet may be permitted to expand under the influence of heat, so that no distortion of 20 the electrode takes place which would impair the space relations between the several electrodes necessary for proper functioning.

The invention comprises a gas tight envelope having the usual glass squash at the bottom and an upright glass standard or arbor within said envelope and attached at its lower end to the squash. Several electrodes are mounted within the envelope adjacent the arbor and are supported at some suitable point, in a substantially rigid manner, by suitable wires, either from the glass arbor or from the squash. This rigid support does not, however, prevent the electrode from expanding under heat and, in order that 35 they may expand and still maintain the proper relations with one another, another connection is provided at a point on the electrodes distant from the rigid supports, said second connection being in the nature of a 40 guiding connection which loosely embraces the portion of the electrode to which it connects, so that in its expansion the particular electrode or electrodes are maintained in their proper position with respect to the 45 other.

In the figure, which is an elevation showing the enclosing envelope partly cut away, one form of tube, employing my invention, is shown. This invention comprises an 50 evacuated envelope 1, preferably of glass, which has at its lower end the usual glass squash portion 2. Extending vertically into the evacuated envelope and attached at its lower end to the squash is an upright standard or arbor 3, preferably of glass, which is

provided with suitable means for supporting or guiding the various electrodes. Within the envelope 1 are several electrodes, a filament 4, a grid structure 5 and a plate 6. These are connected to the proper power circuits, respectively, by means of leading in wires 7, 8, 9, 10 and 11. The electrodes, as a group, are arranged preferably in substantially parallel planes at a point above the end of the squash 2 and adjacent and to the 60 side of the end of the arbor 3. The filament 4, as shown, is preferably shaped in the form of the letter M, the three lower portions of which are connected to the leading in wires 7, 8 and 9, respectively, and the 65 two upper portions of which are connected to suitable resilient wires 12 and 13 which are looped around the upper end of the filament, and the other ends of which resilient wires are embedded in the upper portion of 70 the glass arbor 3. The resiliency of these wires causes the filament to be maintained constantly in a suitable state of tension and this tension is maintained under all temperature conditions of the filament. The grid 80 structure 5 is in the form of a double surface grid having two surfaces 14 and 15, each surface being provided with flanges 16 and 17 to provide additional strength for the grid surfaces. Each of the surfaces 14 and 85 15 are connected at the adjacent ends of the flange portions by suitable connecting members 18, 18' and 19, 19' which are likewise flanged. To one of the lower connecting flange portions the leading in wire 10 is connected. A pair of supporting wires 20 and 21, of heavier material preferably than the leading in wire, are embedded at one end in the squash portion 2 and connected at the 90 other end to the lower connecting flange portions 18' and 19' of the grid. These wires 20 and 21 provide a rigid support for the grid at its lower end. Extending vertically from the upper connecting flange portions of the grid are two wires 22 and 23. These 95 100 are loosely embraced by loops in the ends of wires 24 and 25 which, at their other ends, are embedded in the glass arbor 3. The looped portions of the wires 24 and 25 provide means for preventing any lateral displacement of the grid and at the same time permit a longitudinal expansion of the grid as a whole, under the influence of heat.

The plate electrode 6 comprises two rectangular portions 26 and 27 having their 110

longitudinal edges flanged to provide proper reenforcement as well as a surface of contact for wires 28, 29, and two similar wires of the other side not shown which 5 are welded to the flanges and connect the two electrodes and maintain them in a rigid space relation with each other. The leading in wire 11 is connected to any suitable portion of one or the other plate electrode, the 10 particular portion to which it is attached not being shown in the figure. Extending from a mid-portion of the glass arbor 3 is a pair of wires 32 and 33 which are welded to the flanged edges of the rectangular surface 27 which is, of the two, nearer to the 15 glass arbor 3. The upper portion of the rectangular plate surface 27 is provided with two extending portions 34 and 35. Partially embracing these end portions are 20 the ends of wires 36 and 37 which extend from the glass arbor 3 and are embedded at their other ends therein. These wires 36 and 37, in a manner similar to the wires 24 and 25, afford means whereby the plate 25 structure is maintained in its proper space relation with respect to the other electrodes and, at the same time, permitted to expand under heat so that no lateral distortion takes place. The electrodes might, without 30 departing from the spirit of the invention, be rigidly supported from their upper ends and yieldingly guided from their lower ends although this change, which is obvious, is 35 not shown.

It will be noted, therefore, that this invention provides several electrodes which are supported rigidly at one portion from a supporting arbor and are loosely guided at another point by other connections, so 40 that they are maintained in substantial, vertical and lateral alignment with respect to one another and consequently function properly.

What is claimed is:

- 45 1. An electron discharge device comprising a gas tight envelope, several electrodes within said envelope, rigid supporting connections for said electrodes, and a loose guiding connection for certain of said electrodes.
- 50 2. An electron discharge device comprising a gas tight envelope, several electrodes within said envelope, a support for said electrodes within said envelope, a substantially rigid connection between said electrodes and said support at one point, and a loose guiding connection between certain of said electrodes and said support at another point.
- 55 3. An electron discharge device comprising a gas tight envelope, several electrodes in said envelope, means for supporting said electrodes in definite space relations comprising a supporting arbor in said envelope, rigid connecting wires from said arbor

to said electrodes at one end thereof, and loose guiding connecting wires from said arbor to certain of said electrodes at the other end thereof.

4. An electron discharge device comprising a gas tight envelope having a squash portion therein, several electrodes within said envelope above said squash and adapted to maintain definite space relations, an electrode supporting arbor attached at its 75 lower end to said squash and extending upwardly adjacent said electrodes, a plurality of rigid supporting wires for one end of said electrodes extending from said squash and said arbor to said electrodes, and a plurality of connecting wires loosely embracing the other ends of said electrodes and extending thereto from said arbor and adapted to permit expansion of said electrodes while maintaining their proper space relations. 80

5. An electron discharge device comprising a gas tight envelope, several electrodes within said envelope, rigid supporting connections for said electrodes and a loose 90 guiding connection for one of said electrodes.

6. An electron discharge device comprising cathode, anode and grid electrodes and a guiding connection for one of said electrodes, which permits said electrode to expand and contract while maintaining said electrode in proper space relation with respect to the other electrodes. 95

7. An electron discharge device comprising 100 cathode, anode, and grid electrodes and guiding connections for said grid and anode which permit said electrodes to expand and contract while maintaining said electrodes in proper space relation with respect to 105 each other and the other electrode.

8. An electron discharge device comprising a gas tight envelope having a squash portion therein, several electrodes within said envelope above said squash portion and 110 adapted to be maintained in definite space relations, an electrode supporting arbor attached at its lower end to said squash portion and extending upwardly adjacent said electrodes, a plurality of rigid supporting 115 wires for one end of said electrodes extending from said squash and said arbor to said electrodes, and a connecting wire loosely embracing the other end of one of said electrodes and extending thereto from said arbor and adapted to permit expansion of said electrode while maintaining its proper space relation with respect to the other electrodes. 120

9. An electron discharge device comprising 125 anode, cathode and control electrodes, means for comparatively rigidly supporting one of said electrodes to one portion thereof, and means yieldingly supporting said electrodes at another portion thereof, said yield- 130

- ing support comprising an apertured member and another member embraced thereby.
10. An electron discharge device comprising anode, cathode and control electrodes, means for comparatively rigidly supporting said grid electrode at one portion thereof, and means for slidably supporting said grid electrode at another portion thereof.
11. An electron discharge device comprising anode, cathode and control electrodes, means for comparatively rigidly supporting said anode at one portion thereof, and means for slidably supporting said anode at another portion thereof.
12. An electron discharge device comprising anode, cathode and control electrodes, said anode and control electrodes presenting plane parallel active surfaces, and means for maintaining the parallel relation of said surfaces while permitting them to expand and contract.
13. An electron discharge device comprising anode, cathode and control electrodes, a plurality of said electrodes presenting plane parallel active surfaces, and means for maintaining the parallel relation of said plurality of electrodes while permitting them to expand and contract.
14. An electron discharge device comprising an anode and a cathode presenting parallel active surfaces, and means for maintaining the parallel relation of said surfaces while permitting them to expand and contract.
15. An electron discharge device comprising anode, cathode and control electrodes, said electrodes presenting parallel active surfaces, and means for maintaining the parallel relation of said surfaces while permitting them to expand and contract.
16. An electron discharge device comprising anode, cathode and control electrodes,
- means for comparatively rigidly supporting said electrodes at one portion thereof, and means for yieldingly supporting certain of said electrodes at another portion thereof.
17. An electron discharge device comprising anode and cathode electrodes, means for comparatively rigidly supporting said electrodes at one portion thereof, and means for yieldingly supporting certain of said electrodes at another portion thereof.
18. An electron discharge device comprising a cathode, a grid and an anode, and means for compensating for expansion of said grid and anode whereby a uniform distance is maintained therebetween.
19. An electron discharge device comprising a cathode, a grid and an anode, and means for compensating for expansion of said anode whereby a uniform distance is maintained between said grid and said anode.
20. An electron discharge device comprising a cathode, a control electrode and an anode, said control electrode comprising a plurality of parallel members, and means for compensating for expansion of said control electrode whereby a uniform distance is maintained between said control electrode and said anode.
21. An electron discharge device comprising a cathode, a control electrode comprising a set of parallel members arranged on each side of said cathode, a pair of anode plates arranged exteriorly of said control electrode, and means for compensating for expansion of said control electrode whereby a uniform distance is maintained between said control electrode and said other electrode.

In witness whereof, I hereunto subscribe my name this 18th day of October A. D. 1918.

HOWARD W. WEINHART.
